GOLF BALL WASHING AND DISPENSING MACHINE OR THE LIKE

Fred A. Akel, 13301 Beach Blvd.,
Jacksonville, Fla. 32216

Filed Jan. 24, 1974, Ser. No. 436,087

Term of patent 14 years

Int. Cl. D15—05

U.S. Cl. D49—11

FIG.1

FIG. 2

FIG. 3

FIG. 4

FIG.5

FIG.6

FIG.7

FIG. 1 is a right side elevational view of the golf ball washing and dispensing machine, with the drum located in the washing position, showing my new design;

FIG. 2 is a top plan view thereof;

FIG. 3 is a front end elevational view thereof;

FIG. 4 is a rear end elevational view thereof;

FIG. 5 is a left side elevational view thereof;

FIG. 6 is a bottom view thereof; and

FIG. 7 is a right side elevational view substantially identical to FIG. 1, with the drum in its open and ball dispensing position.

I claim:

The ornamental design for a golf ball washing and dispensing machine or the like, substantially as shown and described.
